C. G. ALDRICH

METHOD OF MAKING LEATHER CASES

Filed May 5, 1926

Patented Dec. 25, 1928.

1,696,788

UNITED STATES PATENT OFFICE.

CARL G. ALDRICH, OF MEDFORD, MASSACHUSETTS.

METHOD OF MAKING LEATHER CASES.

Application filed May 5, 1926. Serial No. 106,918.

My invention relates to a method of making leather cases or containers such, for example as are provided and used for holding eyeglasses and spectacles, and particularly

- 5 to eyeglass cases of that type which are made from one piece of pliable leather having one end portion folded back onto the body portion and stitched thereto along its side edges to form a pouch, the opposite end
- 10 portion providing a flap to be folded back or down onto the first end portion to serve as a closure. Ordinarily cases of this type are provided with a snap fastener for securing the flap in its closed position.

15 My invention has for its object to provide an improved method of making a leather case of the class referred to and also to improve the seams, and preferably the lower corners also if the case has the same, where-
20 by the latter is greatly improved in appearance as compared with those heretofore produced, and certain other mechanical advantages, hereinafter referred to, are se- cured.

25 My improved method of making leather cases is fully set forth in the following description and the novel features thereof are particularly pointed out and defined in the claims at the close of the description.

30 In the accompanying drawings:

Figure 1 is a plan view of a leather blank from which the improved eyeglass case herein shown is made.

Figure 2 shows the blank of Fig. 1 with one end portion thereof folded back onto the body portion and stitched thereto to form the pouch.

Figure 3 is a perspective view of one side portion of the pouch shown in Fig. 2.

40 Figure 4 shows, in perspective, the same side after being treated in accordance with my invention.

Figure 5 is a sectional view of the two dies, hereinafter described, by means of which the effect shown in Fig. 4 is secured.

Figure 6 is a section, enlarged, on line $w-w$ of Fig. 2.

Figure 7 is a section, enlarged, on line $y-y$ of Fig. 5.

50 Figure 8 illustrates the form and construction of the pouch after being operated upon by the dies as in Fig. 7.

Figure 8^a is a sectional detail hereinafter described.

55 Figure 9 is a section on line $x-x$ of Fig.

5 but with the pouch in position between the dies.

Figure 10 is a view similar to Fig. 9 but with the pouch removed.

In manufacturing eyeglass cases of the class referred to, the practice has been to produce a leather blank of approximately, but not exactly, the shape and proportions shown in Fig. 1; then to fold one end portion 1 back onto the body portion 2 along the dot-and-dash line 4; then to fasten each side of the portion 1 to the body portion by lines of stitches 5 which, however, have heretofore extended in a straight line across the portions 1 and 2 and were not curved as at 6 in Fig. 2, and lastly, to rivet the stud and socket members of a snap fastener in the holes 7 and 8, respectively, and the case was completed. In order to guide the operator in making the fold on the line 4 it has heretofore been customary to form the blank, Fig. 1, with a small V-shaped notch at each end of the line 4, but this notch, as heretofore made and used, was very small—

perhaps one-thirty-second of an inch deep—
and served no other purpose than to guide
the operator in making the fold 4, with
the result that when the case was com-
pleted its two walls 1 and 2 lay flatwise
against each other throughout their extent,
and the corners at the bottom of the pouch
formed by them were sharp and flat, the
two notches referred to being practically in-
visible and intended to be so.

The objections to this old style case were that its hard, sharp bottom corners would wear and injure the clothing of the person carrying the case; the operation of inserting the glasses within the pouch was comparatively difficult because of the two walls 1 and 2 lying close together; and the raw unfinished side edges of the walls 1 and 2 adjacent the stitches and the depth of the flaps outside of the latter, were unsightly. All of the objections noted characterized eyeglass cases and the like as heretofore constructed which were of oblong or rectangular shape and made from pliable and comparatively thin leather, which is the type of case with which my invention is chiefly concerned.

In proceeding in accordance with my invention, the blank shown in Fig. 1 is made with V-shaped notches 9 at the opposite ends of the line 4 which are much deeper than 110

the notches heretofore made, being about three-sixteenths or one-quarter of an inch deep. When this blank is folded on the line 4 as shown in Fig. 2 the notches 9 provide blunt or beveled corners 9^a and the lines of stitches 5 are curved at their lower ends as at 6 so as to follow practically parallel with the side edges of the portion 1 throughout its length as shown in Figs. 2 and 3. One side of the pouch thus formed is then drawn over a fixed male die 10 having a rounded corner forming portion as shown in Fig. 5, after which a second heated female die 11 of counterpart shape is forcibly applied to the exterior of the seamed side of the pouch, to the corner, and to the bottom portion of the pouch, said dies being shaped to engage the bottom portion of the pouch as shown in Fig. 9 and to engage the side seamed portion as shown in Fig. 7. As shown in Fig. 9 the edge of the bottom engaging portion of the die 10 is merely shaped with a plain transversely rounded surface while the cooperating part of the die 11 is a plain groove whose surface is parallel with the opposed surface of the die 10. As shown in Figs. 7 and 10 the side-seam engaging edge of die 10 is likewise rounded but extending longitudinally at the middle of this edge is a shallow groove 12, Fig. 10. This groove 12 is disposed directly opposite a shallow groove 13 formed longitudinally throughout the length of the side-seam engaging edge or portion of the die 11. The grooves 12 and 13 are of uniform depth from their open outer ends up to the beginning of the corner forming curved portions of the dies from which points their depths gradually diminish so that the grooves disappear or terminate at or near the bottom engaging portions of the dies. When the pouch of the case is drawn onto the die 10 the two walls 1 and 2, Fig. 6, are spread apart, leaving the two flaps 1^a and 2^a that are outside of stitches 5, projecting perpendicularly outwardly relatively to the edge of die 10. Now, when the die 11 is forced down onto the seamed side of the pouch the groove 13 first pockets the free edges of the flaps 1^a and 2^a throughout their lengths thereby preventing them from separating, and also from being displaced sidewise one way or the other. Simultaneously, on the inside of the pouch, the parts 1 and 2 adjacent the stitches 5 are bent down into the groove 12 around the side walls of the latter, thereby preventing those portions from slipping sidewise apart and breaking the stitches when subjected to the greatest pressure from the die 11. The result is that the two flaps 1^a and 2^a, Fig. 6, are greatly compressed and condensed edgewise without injurious strain upon the stitches, and are molded into a straight bead 14 of uniform height, Figs. 4 and 8, which at its lower end

gradually merges into the surface of the smooth rounded corner 9^b, Fig. 4, produced by the dies, the beveling 9^a, Fig. 2, preventing the formation of any unsightly folds or wrinkles. At the same time the application of the heated metal die 11 to the flaps 1^a and 2^a, gives to the outer edges of the latter a highly desirable glazed finished surface, while the two dies co-operate to set and mold the portions of the walls 1 and 2 adjacent, and at each side of, the seams, as well as at the corners of the pouch, into a well rounded shape which not only greatly improves the appearance of the case, but disposes the two walls 1 and 2 in a separated relationship which permits of easy insertion and withdrawal of the glasses. 75

The successful molding, compressing and finishing of the flaps 1^a and 2^a without destruction of the stitches 5 cannot be accomplished without the co-operating grooves 13 and 12, the former giving to the bead 14 a predetermined shape overlying and sometimes covering the stitches 5; a smooth glossy finish, and uniform height and alignment throughout its length except at the rounded corner 9^b, and the latter preventing the parts 1 and 2 from spreading apart and breaking the stitches when the pressure of the dies is applied. 85

It is true that in the leather working art it is common practice to mold the ends or sides of leather pouches, bags and the like, but always, so far as I know, this operation has been carried out separately and independently of the seam finishing. It is also true that the seams of articles of the kind herein referred to have been burnished, ironed down and shaped by means of a grooved heated hand tool rubbed against the edges of the flaps 1^a and 2^a, but not only has this been an operation that was carried out separately also, but being a manual operation carried out progressively along the seam, no problem of breakage of the stitches was 110 present as in the present case where the entire side adjacent the seam, the corner and the seam throughout its entire length, are simultaneously molded and finished, requiring the application of such great pressure 115 that, except for the groove 12, the stitches would be broken. It will thus be seen that a distinguishing feature of my new method consists in simultaneously compressing and condensing edgewise, and shaping, the flaps 1^a and 2^a of the seam throughout their lengths, or a considerable portion thereof, while holding the two members 1 and 2 against separating or spreading apart under the influence of the crushing effects imposed on flaps 1^a and 2^a, so that the stitches are not broken. It will also be seen that a further feature of the method described above consists in molding to a fixed and predetermined shape, the corner and the portions of the 125 130

members 1 and 2 alongside the seam, simultaneously with the just described condensing, compressing and shaping of the seam flaps 1^a and 2^a throughout their lengths.

5 The shape given to the pouch by the molding operation described above, not only fixes the walls 1 and 2 permanently in spaced apart relationship which permits of easy insertion and removal of the glasses as stated 10 above, but it also provides for the accommodation within the pouch of a spring metal reinforcing bow frame not shown.

What I claim is:

1. The method of finishing the seam connecting the marginal portions of the walls of a leather case of the character described which consists in compressing the two flaps of the seam edgewise simultaneously throughout their length and width while 20 they are left free to expand laterally in the direction of their thickness thereby molding said flaps into a relatively low finished bead whose opposite sides overlie the stitches of the seam.

25 2. The method of finishing the seam connecting the marginal portions of the walls of a leather case of the character described which consists in compressing the two flaps of the seam edgewise simultaneously 30 throughout their length and width while they are left free to expand laterally in the direction of their thickness and while the portions of the two walls at the opposite sides of, and immediately adjacent, the seam 35 are held against displacement away from the seam under pressure applied to the flaps thereby molding said flaps into a relatively low finished bead whose opposite sides overlie the stitches of the seam.

40 3. The method of making a leather case of the character described which consists in compressing the two flaps of the seam edgewise simultaneously throughout their length and width while they are left free to expand 45 laterally in the direction of their thickness thereby molding said flaps into a relatively low finished bead whose opposite sides overlie the stitches of the seam, and simultaneously molding the two walls to spread apart 50 and fix the portions thereof at opposite sides of the seam, and immediately adjacent the flaps, in positions each approximately at right angles to its flap.

45 4. The method of making a leather case of the character described which consists in compressing the two flaps of the seam edge-

wise simultaneously throughout their length and width while they are left free to expand laterally in the direction of their thickness thereby molding said flaps into a relatively 60 low finished bead whose opposite sides overlie the stitches of the seam and simultaneously molding the two walls to spread apart and fix the portions thereof at opposite sides of the seam, and immediately adjacent 65 the flaps, in positions each approximately at right angles to its flap and to fix the major body portions of said walls in relatively parallel spaced apart relationship.

5. The method of making a leather case of 70 the character described which consists in compressing the two flaps of each side seam edgewise simultaneously throughout their length and width while they are left free to expand laterally in the direction of their 75 thickness thereby molding said flaps into a relatively low finished bead whose opposite sides overlie the stitches of the seam and also simultaneously molding the two walls of the pouch in fixed spaced apart and parallel relationship with the portions thereof immediately adjacent the seams, each fixed approximately at right angles to its flaps and with rounded corners at the bottom of the pouch into which the finished beads are merged at 80 their lower ends.

6. The method of making a leather case of the character described which consists in first producing a leather blank having opposite parallel side edges formed intermediate their lengths with V-shaped fold-indicating and corner-rounding notches; then folding said blank upon itself transversely on a line connecting said notches to provide two walls disposed side by side 90 with their edges registering; then securing together each pair of side marginal portions of said walls, by a line of stitches paralleling the adjacent side edges and providing flaps between said line of stitches and said side 95 edges and then compressing each pair of flaps edgewise throughout their lengths and widths and expanding the same laterally in the direction of their thickness thereby constituting a relatively low finished bead whose 100 opposite sides overlie the stitches of the seam, while simultaneously fixing the portions of said walls immediately adjoining each seam in positions each approximately 105 at right angles to its flap.

CARL G. ALDRICH.
